CLAIM

The ornamental design for a display screen or portion thereof with animated graphical user interface, as shown and described.

DESCRIPTION

1.1 : First image
1.2 : Second image
1.3 : Third image
2.1 : First image
2.2 : Second image
2.3 : Third image
3.1 : First image
3.2 : Second image
3.3 : Third image
4.1 : First image
4.2 : Second image
4.3 : Third image
5.1 : First image
5.2 : Second image
5.3 : Third image
5.4 : Fourth image
6.1 : First image
6.2 : Second image
6.3 : Third image
6.4 : Fourth image

The appearance of the animated graphical user interfaces sequentially transitions between the images, as shown in reproductions 1.1 to 1.3, 2.1 to 2.3, 3.1 to 3.3, 4.1 to 4.3, 5.1 to 5.4, and 6.1 to 6.4; the process or period between which one image transitions to another forms no part of the claimed design; the broken line showing of the phone and the display screen or a portion thereof is for the purpose of illustrating the environment and forms no part of the claimed design; the broken line showing of elements on the display screen illustrate portions of the graphical user interface and form no part of the claimed design.

1 Claim, 20 Drawing Sheets
